UNITED STATES PATENT OFFICE.

MAX BRAMSON, OF WARSAW, RUSSIA, ASSIGNOR TO HENRY F. VOGEL, OF ST. LOUIS, MISSOURI.

PETROLEUM INCANDESCENT-LIGHT BURNER.

SPECIFICATION forming part of Letters Patent No. 709,198, dated September 16, 1902.

Application filed June 24, 1901. Serial No. 65,810. (No model.)

To all whom it may concern:

Be it known that I, MAX BRAMSON, a subject of the Czar of Russia, and a resident of the city of Warsaw, Russian Poland, in the 5 Empire of Russia, have invented certain new and useful Improvements in Petroleum Incandescent-Light Burners, of which the following is a full, clear, and exact description, reference being had to the accompanying 10 drawings, forming part of this specification.

My invention relates to a burner for use upon petroleum-lamps to produce an incandescent or white light in the operation of said burner; and the invention consists in features of novelty hereinafter fully described, 15 and pointed out in the claims.

Petroleum incandescent-light burners as heretofore in use show defects, which it is the object of my invention to overcome. In order 20 to produce a blue flame in a burner of the class named, it is requisite that the wick-tube be first heated by means of the ordinary yellow petroleum-flame, which operation requires at least three or four minutes. The 25 blue flame that is then obtained must be carefully regulated, which requires practice and patience. After the burner has been heated, during the period of the accomplishment of which the light effect has been raised or lowered, 30 the body of the mantle of refractory material utilized to produce the incandescent light desired begins to blacken with a smutty substance, and if the wick is not immediately regulated with regard to height the entire 35 mantle will become blackened, and it is possible at times that an explosion of the lamp, reservoir will occur. The burner also becomes heated to such a degree that it cannot be touched without burning the hands, and 40 by reason of the incomplete consumption of the petroleum the lamp emits an unpleasant and at times an unhealthy odor.

The faults and defects above enumerated are entirely removed in a burner constructed 45 in accordance with my invention, inasmuch as the construction of my burner is such that the blue flame is immediately obtained and sustained, and consequently complete combustion of the petroleum is maintained 50 throughout the operation of the burner from the start and blackening of the mantle is pre-

vented, this result being occasioned by reason of the fact that the wick is raised always to a determined height and maintained at such height throughout the operation of the 55 burner and the necessity of first heating the burner or burner-tube is avoided. I obtain the results desired by the burner construction which will now be described.

Figure I is a vertical sectional view taken 60 through my improved burner with portions shown in elevation. Fig. II is a top view of the cap that surmounts the cone of the burner. Fig. III is a view, partly in elevation and partly in vertical section, of the cap shown in 65 Fig. II. Fig. IV is a detail view of the ring seated in the upper end of the cone of the burner. Fig. V is a cross-sectional view taken on line V V, Fig. IV. Fig. VI is a top view of the burner-cone. Fig. VII is a view 70 in elevation and partly in section of the burner-cone. Fig. VIII is a sectional view of a modification of the burner.

1 designates the lamp-font, which is provided with an outer wick-tube 2 and an inner 75 wick-tube 3, the inner tube 3 being of less height than the outer tube, as clearly seen in Fig. I.

4 is the wick, positioned between the inner and outer tubes 2 and 3. 80

6 is a perforate air-distributer, to which air passes through the font.

7 designates a cone provided with an annular shoulder 8 and curving inwardly from said shoulder to a contracted neck 9. In the 85 curving portion of the cone between the shoulder 8 and the neck 9 are a series of apertures 10. The neck 9 of the cone is provided with an interior flange 11, that rests upon the upper end of the outer wick-tube 2 and is 90 adapted to serve as a stop for the wick 4 to limit the elevation thereof and prevent the flame burning from the wick from being directed upwardly, but instead causing the flame to burn at the side of the wick and in 95 a direction toward the air-distributer 6. Above the flange 11 is an annular shoulder 12 within the cone-neck 9, and on this shoulder is supported a ring 13, composed of material of greater heat conductivity than the burner, 100 such as copper, and from which the heat received thereby is readily deflected to act in

conjunction with the air-distributer 6 in turning the products of combustion of the petroleum into gas.

14 designates a conical cap having a central opening 15, that fits over the upper end of the cone-neck 9, while the lower end thereof seats upon the annular shoulder 8 of the cone 7.

18 is the chimney, mounted on the cone 7. 10 In the wall of the cone-cap 14 are a series of apertures 16, through which heated air from the interior of the chimney enters the mixing-chamber A between the cone-cap and the cone 7 to mix with the fresh air that 15 enters said chamber through the apertures 10 in the curving part of the cone. It will be seen that these two cones or caps form a member having an air-mixing chamber. The two currents of air will become mixed in said 20 space, pass upwardly and through apertures 17 in the top of the cone-cap 14 to mix with the blue flame produced in the operation of the burner. By the introduction of air in this manner in a mixture of heated and fresh 25 air an air-current is produced that enters into contact with the blue flame in such manner as to avoid cooling or overheating of the burner.

19 designates the refractory mantle, the lower end of which fits over the cone-cap 14 30 and which is supported by a post 20.

In the practical use of the burner the wick is first raised to the annular flange 11, as seen in Fig. I, and on the removal of the cone 7, with the parts of the burner associated therewith, the oil in the wick is ignited. The cone, together with the other parts of the burner carried thereby, is then replaced, and the flame burns at the side of the wick, being projected toward the distributer 6. The flame 40 mixes with the air which enters through the perforate air-distributer and extends upwardly, contacting with the ring 13, of readily-heated material, and also mixes with the current of air that enters the interior of the 45 mantle 19 from the mixing-chamber A through the apertures 17 in the cone-cap 14. By this arrangement the blue flame is produced initially and maintained, and it is unnecessary to regulate the wick at any time 50 during the period that the lamp is in use. The burner remains cool throughout its use, and the petroleum is entirely consumed, thereby avoiding the production of disagreeable odors.

55 In Fig. VIII, I have shown a modification wherein the cone-cap 14^a is not apertured at its upper end, but is provided with the apertures 16^a in its wall. In this form of construction the ring 13^a, of easily-heated material, is mounted upon the cone-cap 14^a instead of upon the neck 9 of the cone. The air enters the space between the cone and the cone-cap through the perforations 16^a in said cap and through the perforations 10^a in the 60 cone and passes inwardly between the flange 12^a and the upper end of the cone-cap and ring 13^a directly to the deflector 6^a and through

the ring 13^a. The wick-tubes 2^a and 3^a are of the same construction as shown in Fig. I.

I claim as my invention—

1. In a burner, the combination with a mantle and the wick-tube, of a detachable member supported upon the upper end of the wick-tube and having an air-mixing chamber, inlets to said chamber for cold air and for hot 75 air and an outlet for the mixed air communicating with the interior of the mantle.

2. In a burner of the class described, the combination with a chimney, a wick-tube, and a mantle, of a pair of apertured caps forming 80 a detachable member, which is supported upon the upper end of the wick-tube, and has an air-mixing chamber receiving fresh and heated air, one of said caps being provided with apertures through which the air passes 85 from said mixing-chamber to the interior of said mantle.

3. In a burner, the combination with a mantle and the wick-tube, of a detachable member supported upon the upper end of the 90 wick-tube and having an air-mixing chamber, inlets to said chamber for cold air and for hot air and an outlet for the mixed air communicating with the interior of the mantle, and a copper ring supported above the wick-tube. 95

4. In a burner of the class described, the combination of an outer wick-tube, an inner wick-tube of less height than said outer tube, a cone fitting over said outer tube and having an annular flange arranged to project 100 over a wick positioned between said tubes, and a mantle; said cone being provided with apertures for the admission of air thereinto, substantially as described.

5. In a burner of the class described, the 105 combination of an outer wick-tube, an inner wick-tube of less height than said outer tube, a cone fitted to said outer wick-tube, a flange on the interior of said cone arranged to project over the wick positioned between said 110 wick-tubes, a cone-cap mounted on said cone, and a mantle; said cone and cone-cap being provided with apertures for the admission of air to the interior of the mantle, substantially as described. 115

6. In a burner of the class described, the combination of an outer wick-tube, an inner wick-tube of less height than said outer tube, an apertured cone fitting over said outer wick-tube, an annular flange on the interior 120 of said cone arranged to project over the upper end of the wick positioned between said wick-tubes, a cone-cap provided with apertures in its wall and in its upper end, and a mantle, substantially as described. 125

7. In a burner of the class described, the combination of an outer wick-tube, an inner wick-tube of less height than said outer tube, an air-distributer positioned within said inner tube, an apertured cone fitting over said 130 outer wick-tube, an annular flange on the interior of said cone arranged to project over the upper end of the wick positioned between said wick-tubes, an apertured cone-cap sur-

mounting said cone, and a mantle, substantially as described.

8. In a burner of the class described, the combination of an outer wick-tube, an inner wick-tube of less height than said outer tube, an apertured cone fitting over said outer wick-tube, an annular flange within said cone and arranged to project over the end of the wick positioned between said wick-tubes, an apertured cone-cap mounted on said cone, and an air-distributer positioned within said wick-tubes, a ring of material of greater heat conductivity than the burner surmounting the upper end of the wick-tubes, and a mantle, substantially as described.

9. The combination with a mantle, of a burner having air-inlets leading to the interior of the mantle, and an air-heating device

composed of copper and located adjacent to said inlets and heating the air as it passes 20 into the mantle.

10. The combination of a mantle, and a burner having an air-mixing chamber, the side walls of which extend to the top of the burner, an inlet to said chamber for cold air, 25 an inlet to said chamber for conducting the hot air around said mantle into the mixing-chamber, and an outlet for mixed air communicating with the interior of the mantle between the burner and the inner face of the 30 mantle.

MAX BRAMSON.
